UNITED STATES PATENT OFFICE

WILLIAM MELDE, OF MARENGO, ILLINOIS.

MOLDING-MACHINE FOR ROOFING-TILES.

1,114,168.

Specification of Letters Patent.

Patented Oct. 20, 1914.

Application filed July 17, 1913. Serial No. 779,647.

To all whom it may concern:

Be it known that I, WILLIAM MELDE, a citizen of the United States, residing at Marengo, in the county of McHenry and State of Illinois, have invented certain new and useful Improvements in Molding-Machines for Roofing-Tiles; and I do declare the following to be a full, clear, and exact description of the invention; such as will enable others skilled in the art to which it appertains to make and use the same.

This invention relates to molding machines, and more especially to those adapted for the formation of roofing tiles; and the objects of the same are to effect improvements in the means for sanding or finishing the face of a tile and in the means for forming the eye or perforation through the web thereof. These objects are carried out by the incorporation of a novel form of sander and a novel means for actuating the needle. The invention also consists of other details of construction as will be described in the following specification and as are shown in the drawings wherein—

Figure 1 is a plan view of this machine complete, and Fig. 2 is a side elevation thereof, both omitting the pallet. Fig. 3 is a longitudinal central section through the machine, with the cutter in action; and Fig. 4 is a transverse section of said machine on the line 4—4 of Fig. 3. Fig. 5 is a longitudinal section through the box or sifter. Figs. 6, 7, and 8 are perspective details respectively of the box or frame, the cutter, and the shaper. Fig. 9 is a perspective detail of the needle, and Fig. 10 is a perspective detail of the lever for retracting the needle.

In the drawings are shown legs 1 supporting a table top 2 having an opening in it and cross bars 3 across said opening carrying a frame 4. Secured to the ends of the cross bars 3 are rails 7 which extend alongside the opening and beyond one end of the table as shown. Mounted in the cross bars are supporting screws 8 on which the pallet 9 is supported when it is placed within the frame, and slidably mounted through said cross bars are pins 10 whose lower ends are suitably connected as at 11 with a treadle 12 so that when the latter is depressed the pins will rise and lift the pallet out of the frame and therefore off of the supporting screws 8. Adjustment of the latter causes the pallet to stand higher or lower within the frame

and therefore causes the machine to produce thinner or thicker tiles as will be explained below.

The numeral 14 designates a shaper having handles at its extremities and near them guides 15 which slide on the upper edges of the rails 7 as the shaper is drawn across the frame 4. The lower edge of this shaper is made to conform with the upper face of the finished tile, as the upper face of the pallet is made to conform with its lower face, and the configurations of these parts will be modified to suit the type of tile being produced by the machine. The shaper is by preference of metal and it is used to tamp the material down onto the pallet plate and within the mold in the well known manner, as well as to scrape off the surplus when necessary.

The tile in the process of formation by this machine is designated in the drawings by the reference letter T. While the same is shown in the drawings as substantially flat, its configuration may obviously be modified by substituting another pallet and using another shaper, and in fact the machine might be employed for making other articles than tiles although that is its preferred use and I have so shown and described it.

The knife 20 in the present case is rectangular in configuration and of a size to pass just outside the frame 4. At one end it is rigidly mounted on a bail 21 whose downturned extremities 22 are pivoted at 23 in supports 24 rising from the table top 2, and the other end of the knife carries a handle 25 by which it is manipulated. The size and shape of parts and the disposition of the pivots are such that when the knife is brought down it passes just outside the frame 4 and shears off the surplus material in a manner well understood.

The sander or finisher in the present case is composed of a box-like structure 30 mounted on wheels 31 which travel on the rails 7, so that the entire box is passed beneath the bail 21 when the knife is raised as shown, and hence both the sander and the knife stand at the rear of the machine and out of the way of the operator when working on the tile. The bottom of the box is perforated so as to constitute a sieve 32 having holes one-sixteenth of an inch in size, and over this bottom slides a false bottom 33 perforated with one-eighth inch holes so as to produce another sieve 34 a little shorter

- than the internal length of the box so that it may be reciprocated by means of a handle 35 which extends through the front end of the box to within reach of the operator.
- 5 After the tile has been formed in the manner well known to those familiar with this art, the sander or finisher is brought forward by rolling it along the track until it stands over the tile, the shaper being then 10 of course removed. The sand or cement or other finishing material being within the box 30, the handle 35 is now grasped and the inner or false bottom reciprocated so as to agitate the material, which sifts 15 through the true bottom 32 onto the tile; after which the sander is restored to its normal position. The knife is then brought down to cut off the surplus material around the edges of the pallet, after which the latter with the tile thereon is lifted out of the frame and the tile removed for firing in the kiln, if it is to be fired, or for setting if it is of cement. For lifting the pallet and tile the treadle mechanism above described 20 is employed, and when the operator places his foot on the treadle 12 he raises all the pins 10 so that the pallet is lifted off the screws 8 in a manner which will be clear.
- An important feature of my invention 25 consists in means for forming a hole or eye through one of the webs or ribs in the under side of the tile, if this machine be employed for making roofing tiles as suggested above. In that case, as is well known to those familiar with the art, these holes are necessary for the insertion of the wires or loops by means of which the tiles are subsequently secured to the roofing boards; and the operator having both hands employed, it becomes 30 desirable that some means be present whereby the pin or needle which forms the hole may be projected through the rib and across that portion of the pallet which forms the same, at the right time and without the necessity for the withdrawal of his 35 hands from their position then.
- Referring now more particularly to Figs. 3 and 9, the numeral 40 designates a pin or needle carried by the upper end of an upright arm 41 which rises from a bar 42 slidably mounted in guides 43 in the frame 4, and this bar in turn is connected in any suitable manner with a plunger bar 44, as by means of a second upright arm 45. The 45 plunger bar moves through guides 46 in the frame of the table, and connected with its front end is a plate 47 lying along the edge of the table nearest the operator. When now the latter leans forward sufficiently to bear upon this plate, he moves the plunger bar 44 and the other bar 42, and the latter by means of the arm 41 projects the needle 40 through the rib in the underside of the tile as shown. For 50 retracting the needle I may employ any pre-

ferred means, but as shown in these views there is a bell-crank lever 48 pivoted at its angle at 49 to a suitable support within the frame, its upper arm engaging a stop or pin 50 on the upper sliding bar 40 and its 55 lower arm standing in the path of an upright pin 51 forming part of the connection 11 between the pallet-lifting pins 10 and the treadle mechanism 12. So that when the operator depresses the treadle to 60 raise the pins and lift the pallet out of the frame, the pin 51 will turn the bell crank lever and the upper arm of the latter will strike the pin 50 and slide the bar 42 and withdraw the needle 40 in a manner which 65 will be clear. It follows from this detail of construction, if adopted, that although the operator may lean against the plate 47 and project the needle at any stage in the process of forming the tile, when he comes 70 to eject the tile from the frame the act of lifting the pallet withdraws the needle, and the result is that the hole formed through the rib in the tile is not torn out as so often occurs when the operator takes out a finished 75 tile without first withdrawing the needle. Nevertheless it might be possible to substitute other mechanism for retracting the needle, because after the latter has once been projected and the hole formed, it is 80 not necessary that it remain if the consistency of the composition is correct.

Thus is constructed a light, simple, durable, and yet effective machine for the formation of roofing tiles by a single operator 85 and on a small scale. It will not be necessary for the purpose of this specification to describe the manner of or mechanism for bringing the materials to the operator or for taking away the tile when the latter is 90 to be dried or baked, and obviously the materials, proportions, and exact details of parts are also unimportant.

What is claimed as new is:

1. In a tile forming machine, the combination with a table, a frame carried thereby and a pallet movably mounted on the frame and of a design to form a tile having ribs on its under face; of means for lifting the pallet above the frame, means for piercing one of the ribs on the tile formed and additional means coöperating with the pallet lifting means and the last mentioned means for disposing the latter to its inoperative position upon the disposition of the former 110 to its operative position.

2. In a tile forming machine, the combination with a table, a frame carried thereby and a pallet movably mounted on said frame and of a design to form a rib on the lower face of the tile; of a foot operating means for lifting the pallet above the frame, a movable needle for piercing the rib on the tile formed, manually operable means for disposing the needle to its operative position, 115

and means coöperating with the foot actuated means and manually operated means whereby to actuate the latter upon the actuation of the former to dispose the needle to its inoperative position prior to the lifting of the pallet above the frame.

3. In a tile making machine, the combination with a table, a frame carried thereby, and a pallet removably mounted on the frame and of a configuration to form a tile having a rib along its lower side; of means for lifting the pallet off the frame, a treadle mechanism for actuating said means, a bar movably mounted within the frame, a needle carried thereby for piercing one of the ribs in the tile, a plate across the front of the table, connections between said plate and bar for actuating the latter to project the needle, and connections between said treadle mechanism and plate for retracting the needle in advance of the operation of the lifting means.

4. In a molding machine of the class described, the combination with a table having

an opening in its top, rails extending longitudinally along the sides thereof and projecting beyond one end of the same, a frame within the opening of said top and a pallet and shaper arranged in connection therewith; of a pair of bearings mounted on the table top at one end thereof and just beyond said rails, a crank shaft having the ends thereof pivotally mounted in said bearings to extend transversely of the rails, a cutter carried by the crank shaft and a supply member movably mounted on said rails and adapted for movement under said crank shaft when the cutter member is raised to permit said supply member to be disposed over said frame.

In testimony whereof I have hereunto set my hand in presence of two subscribing witnesses.

WILLIAM MELDE.
